APPARATUS FOR X-RAY PHOTOGRAPHING TUBULAR STEEL CASTINGS

Filed Jan. 12, 1945

UNITED STATES PATENT OFFICE

2,437,688

APPARATUS FOR X-RAY PHOTOGRAPHING
TUBULAR STEEL CASTINGSEric G. Forssell, Kenmore, N. Y., assignor to
W. H. Miner, Inc., Chicago, Ill., a corporation
of Delaware

Application January 12, 1945, Serial No. 572,562

4 Claims. (Cl. 250—65)

1

This invention relates to improvements in apparatus for X-ray photographing tubular steel castings for detecting flaws in such castings.

One object of the invention is to provide an apparatus for X-ray photographing flaws in tubular steel castings comprising a rotary chuck or table on which the tubular steel casting is clamped for rotation therewith, a source of X-rays radial to the axis of rotation of the table and tubular member, a photographic film holder telescoped within the tubular casting for holding a continuous film in close proximity to the inner face of the side walls of the casting, a lead screen between the tubular member and the source of X-rays, the screen having a lengthwise extending, narrow opening therethrough, permitting the free passage of X-rays, thereby confining the action to a relatively narrow field, and means for rotating the table, wherein the side of the film opposite to that being X-rayed is protected by a fixed screen member projecting into the tubular casting and the film holder therewithin and extending lengthwise thereof, the screening member being of a width to exclude all rays passing through the slot of the lead screen.

Other objects of the invention will more clearly appear from the description and claims herein-after following.

In the drawing forming a part of this specification, Figure 1 is a side elevational view of my improved apparatus. Figure 2 is a front elevational view, looking from left to right in Figure 1. Figure 3 is a horizontal, longitudinal sectional view through the center of the tubular casting and film holder, corresponding substantially to the line 3—3 of Figure 1, showing the screening element in plan.

As shown in the drawing, my improved apparatus comprises broadly a supporting frame A; a rotary table or chuck B; a slotted screen C; a hinged table D for supporting the screen; an elongated screening element E; and clamps F—F for fixing the casting to the table B.

The supporting frame A includes a horizontal platform 10, the front end portion of which only is shown in the drawing. The platform is mounted on suitable feet 11, only one of which is shown in Figure 1 of the drawing.

The rotary table or chuck B is in the form of a flat disk-like plate having a rearwardly extending shaft 14 secured thereto, which is rotatably supported in a bearing element 12 carried by an upright standard 13 on the platform 10. The driving means for the shaft is not illustrated but it is such that the shaft 14 is rotated at rela-

tively slow speed. The driving means may be in the form of an electric motor and any well-known type of reduction gearing interposed between and connecting the motor to the shaft 14.

The rotary table or chuck B carries the clamps F—F, which are disposed at opposite sides of the center of rotation of the table and are in the form of hooks having straight shank portions 15 extending through openings in the table B. The shanks 15—15 are threaded at their outer ends to receive clamping nuts 16. At their opposite ends, the clamps F—F are provided with angularly bent portions 17—17 substantially at right angles to the shanks forming the hook members proper of said clamps. The clamps F—F are especially designed to securely mount the particular type of tubular casting 18 herein illustrated, namely, the casing of a railway friction draft gear of well-known design, on the table B. The well-known draft gear referred to comprises briefly the casing 18 and a spring resisted friction clutch slidably in the casing, which is of hexagonal, interior and exterior cross section. This type of casing is provided with the usual openings 19—19 in the sides thereof. In the present instance, these openings are used in clamping the casing 18 to the table B, the hook portions of the clamps F—F being engaged in these openings and the clamps locked to the table 30 by the nuts 16.

The supporting table D for the screen C is in the form of an open rectangular frame having rearwardly extending arms 20—20 hinged at their rear ends to upright columns 21—21 supported by the platform 10. The table D is supported in horizontal position by arms 22—22 of the frame A, which extend forwardly from the columns 21—21, and are braced at their front ends by struts 23—23 extending from the platform 10, the table resting or being supported on upstanding portions 24—24 at the front ends of the arms 22—22.

The screen C, which is supported by the table or frame D, comprises a pair of laterally spaced, 45 thick, lead plates 25—25 supported within the opening of the frame D by clamps 26—26. The plates 25—25 are arranged lengthwise of the axis of rotation of the draft gear casting 18 and the opening between these plates extends lengthwise 50 of the latter, parallel to and in vertical alignment with its axis of rotation.

The X-ray apparatus employed with my improved mechanism is of well-known type and is indicated by 27. As shown in Figure 3, the same 55 is located above the screen C in vertical align-

ment with the axis of rotation of the draft gear casting 18 and the opening of the screen.

A suitable film holder 28, which is in the form of a hollow, tubular member, comprising inner and outer tubular shells between which the film is held, is fitted within the open end of the casting 18.

The screening element E is in the form of a relatively thick lead bar projecting into the opening of the film holder 28 in close proximity to the upper side thereof. The bar E extends horizontally and is supported by a detachable bracket 29 mounted on the platform 19 of the frame A. The bracket 29 includes a laterally inwardly extending foot portion 30 at its lower end secured to the top of the platform by a bolt 31. The bar E is fixed to the upper end of the bracket 29 by a bolt 32 extending through said bar and a laterally outwardly projecting flange 33 on the bracket.

The operation of my improved apparatus is as follows: The tubular steel casting, in this case, the hexagonal casting 18, to be X-rayed, with the film holder 28 therewithin, is mounted on the rotary table or chuck B, being secured by the clamps F-F'. The bracket 29 with the lead screening bar E attached thereto is then fixed in position on the platform 19 with the bar E projecting into the film holder 28, which is within the casting 18. The table D, which has been swung upwardly during the operation of clamping the casting to the chuck B, is then lowered to the horizontal position shown in Figure 1. Power is then applied to the driving shaft 14 to slowly rotate the same and the chuck B together with the casting 18 thereon. At the same time, electric current is supplied to the X-ray apparatus 27, thereby exposing the casting 18 and the photographic film in the holder 28 to the rays emanating from the X-ray apparatus.

In this connection, it is pointed out that the lead bar E properly screens that portion of the photographic film at the side of the film holder opposite to that exposed to the source of X-ray during rotation of the tubular casting, thereby preventing marring of the exposure which would otherwise occur by diffused rays reaching this portion of the film, the bar E being of greater width than the opening of the screen C, that is, of ample width to take care of any diverging rays passing through said opening.

I have herein shown and described what I now consider the preferred manner of carrying out my invention, but the same is merely illustrative and I contemplate all changes and modifications that come within the scope of the claims appended hereto:

I claim:

1. In an apparatus for producing X-ray photographs of tubular steel castings, the combination with a rotary supporting table; of means for transmitting slow rotary motion to said table; means on said table for clamping a tubular steel casting thereon with its central longitudinal axis in alignment with the axis of rotation of the table; a hollow tubular photographic film holder mounted within said casting for rotation in unison therewith, said holder fitting within the tubular casting and having a photographic film arranged annularly therein; a screen of material impervious to X-rays parallel to the axis of rotation of said table at one side of the latter, said screen having an elongated aperture therethrough, the length of said aperture being parallel to said axis of rotation; a screen impervious

to X-rays within said film holder, said second named screen being mounted on a fixed support and being of greater width than said aperture; and an X-ray tube remote from said table, said first named screen being introduced between the X-ray tube and the tubular casting on said table.

2. In an apparatus for producing X-ray photographs of tubular steel castings, the combination with a rotary supporting table; of means for transmitting slow rotary motion to said table; means on said table for clamping a tubular steel casting thereon with its central longitudinal axis in alignment with the axis of rotation of the table; a hollow tubular photographic film holder fitting within the tubular casting for rotation in unison therewith and having a photographic film arranged annularly therein; a screen of material impervious to X-rays parallel to the axis of rotation of said table at one side of the latter, said screen having an elongated aperture therethrough, the length of said aperture being parallel to said axis of rotation; a fixed support; a second screen impervious to X-rays fixed to said support and extending into the hollow portion of said film holder parallel to said axis of rotation, said second named screen being of greater width than said aperture; and X-ray tube remote from said table, said first named screen being interposed between the X-ray tube and the tubular casting on said table.

3. In an apparatus for producing X-ray photographs of tubular steel castings, the combination with a rotary supporting table; of means for transmitting slow rotary motion to said table; means on said table for clamping a tubular steel casting thereon with its central longitudinal axis in alignment with the axis of rotation of the table; a hollow tubular photographic film holder fitting within the tubular casting for rotation in unison therewith and having a photographic film arranged annularly therein; a screen of material impervious to X-rays parallel to the axis of rotation of said table at one side of the latter, said screen having an elongated aperture therethrough, the length of said aperture being parallel to said axis of rotation; a fixed support; an elongated screen impervious to X-rays fixed to said support and extending into the hollow portion of said film holder parallel to said axis of rotation, said second named screen being of a width at least as great as the elongated aperture of said first named screen; and an X-ray tube remote from said table, said first named screen being interposed between the X-ray tube and the tubular casting on said table.

4. In an apparatus for producing X-ray photographs of tubular steel castings, the combination with a table rotatable about a horizontal axis; of means for transmitting rotary motion to said table; means on said table for clamping a tubular steel casting thereon with its central longitudinal axis in alignment with the axis of rotation of the table; an X-ray tube suspended above said tubular casting vertically above the axis of rotation thereof; a stationary horizontal screen interposed between said tubular steel casting and said X-ray tube, said screen being impervious to X-rays and having an elongated narrow opening therethrough, said opening being aligned lengthwise with said axis of rotation; an elongated stationary horizontal screen of greater width than said opening, said elongated screen being mounted below said first named screen in vertical alignment with the opening thereof, said second named screen extending into said tubular cast-

ing; and a hollow tubular film holder mounted within said tubular casting for rotation in unison therewith, said film holder surrounding said second named screen.
